ORE CONCENTRATOR

Ervin O. Oberdick, Cleveland, Ohio, assignor to
Cleveland Tungsten, Inc., a corporation of Ohio

Application November 18, 1941, Serial No. 419,578

4 Claims. (Cl. 209—504)

This invention relates to ore concentrators and more particularly to improved means for shaking or imparting a vibratory movement to the table or deck of such concentrators. The invention also relates to improved means for applying dressing water to the table or deck and to means for adjusting the table to provide the proper transverse inclination.

Ore concentrators which have heretofore been devised for separating mineral from gangue have been provided with complicated means for shaking or jerking the table, such as toggle mechanism, eccentrics, or the like which not only must be accurately adjusted but which materially increase the cost of the table.

It is the aim of the present invention to provide an improved concentrator of this type which is simple in construction, easily adjustable, effective in operation, and the table or deck of which may be vibrated in a simple manner.

Another object of the invention is to provide improved means for imparting head motion to the table for moving the mineral along riffles extending longitudinally upon the deck.

A further object is to provide improved means for adjusting the transverse inclination of the table.

A still further object is to provide improved means for regulating the quantity of dressing water for washing the gangue from the mineral constituent of the ore.

My invention will be better understood by reference to the accompanying drawings in which:

Fig. 1 is a plan view of the table with portions broken away to show underlying structure;

Fig. 2 is a rear side elevational view of the table shown in Fig. 1 with parts broken away to show adjacent structure;

Fig. 3 is a front elevational view of the upper portion of the table showing means for adjusting the inclination of the deck;

Fig. 4 is a diagrammatical view of the table with parts in section, the movable parts being in a position different from that shown in Fig. 2;

Fig. 5 is an end view of the table as seen from a plane on the line 5—5 of Fig. 3, looking in the direction of the arrows;

Fig. 6 is a cross sectional view on the line 6—6 of Fig. 3;

Fig. 7 is a fragmentary plan view as seen from a plane passing through the line 7—7 of Fig. 3 with the movable gates in a partially open position;

Fig. 8 is a cross sectional view on the line 8—8 of Fig. 2;

Fig. 9 is a cross sectional view on the line 9—9 of Fig. 2; and

Fig. 10 is a fragmentary sectional view on the line 10—10 of Fig. 3.

As illustrated in the drawings, the improved concentrator comprises a deck or table 1 provided with a plurality of riffles 2, a feed trough 3 and a water dressing trough 4 supported above the deck, a frame for supporting the deck, and means for imparting a vibrating or oscillating movement to the deck to separate the mineral constituents of the ore from the gangue during the treating operation.

While the deck may be supported by any desirable means and may be of any suitable size and I do not desire to be limited to the particular arrangement shown, as illustrated in the drawings, a frame is provided having lower beams 5 and 6 connected together by cross bars 7, 8, 9, 10 and 11, and a pair of upper beams 12 and 13 secured together by cross bars 14, 15, 16, 17 and 18 which serve to support superimposed cross bars 19, 20, 21 and 22, each of which is hinged at one end to beam 12 as indicated by the numerals 23 and the other end of each of which is supported on inclined plane 23a of a depression or notch formed in a slide 24, the slide being movable longitudinally upon beam 13 between guide pins 25 and being provided at one end with a recess 24a.

For providing a surface on which the ore may be treated, a plurality of spaced longitudinally extending beams indicated by the numerals 26, 27 and 28, support the bottom 29 of the deck over which is superimposed a cover 30 which is preferably formed of linoleum or other suitable material, such as rubber. As illustrated, central beams 26 and 27 rest upon and outer beams 25 and 28 are embedded in cross bars 19 to 22, inclusive, to prevent transverse movement of the deck. The riffles 2 are of usual arrangement and are formed by tacking wooden strips upon the linoleum, or by forming grooves in the cover if a material, such as rubber, is utilized, and are preferably inclined from the forward to the concentrate discharge end of the table and terminate in a substantially feather-like edge along the line X—X.

In utilizing the table for separating the mineral constituents from the ore, ore pulp is supplied to the feed trough 3 and part thereof flows through an opening 36a in the lower portion of a partition 31 into a supplementary feed trough 3a and the pulp flows from both troughs 3 and 3a through openings 32 provided in the side of the

trough adjacent the head or splash board 33 on to the surface of the deck. If desired the openings 32 may be provided with adjustable covers 34 to regulate the flow of pulp as shown more clearly in Fig. 3.

For imparting horizontal movement to the mineral constituents which separate from the gangue and settle in the riffles, the table is inclined downwardly in a longitudinal direction from the breast board 34a to the mineral concentrate end and is supported in such a manner that it may be vibrated or agitated. For this purpose a plurality of spaced flexible members, such as slats 35, are arranged between cross pieces 7 and 14, 9 and 16, and 11 and 18, and are secured thereto by any suitable means, such as strips 36, fastened to the cross bars by means of bolts 37 extending between the slats as shown more particularly in Figs. 2, 8 and 9, and standards 38 and 39 are provided which are secured at their lower ends to cross pieces 8 and 10, respectively, substantially centrally thereof and are braced against movement by means of a beam 40 extending between and embedded in recesses formed in the standards, a tie rod 41, and side braces 42 and 43, the side braces having their lower ends secured to cross piece 9 and their upper ends to standards 38 and 39, respectively.

As illustrated more particularly in Figs. 2 and 4, means are provided to limit the movement of the table in opposite directions and to regulate its movement in accordance with the movement of the actuating mechanism. For this purpose, standard 38 is provided with recess 44 to receive cross bar 17 which limits the movement of the table in one direction and standard 38 is provided with a recess 45 on its opposite side for receiving cross bar 15 which limits the movement of the table in the opposite direction. To regulate the movement of the table, a rod 46 extending through apertures in standard 38 and cross piece 17 is provided with a nut 47 and a spring 48 is compressed between the nut and cross piece 17 and in a like manner a rod 49 extending through apertures in standard 38 and cross piece 15 is provided with a nut 50 and a spring 51 is interposed between the nut and cross piece 15.

The shaking or vibrating movement of the table is effected by means of one or more movable weights associated with the table, the effect of which vary in accordance with the position of the weights with respect to the table and while applicant does not desire to be limited to any particular arrangement, mechanism is shown in the accompanying drawings which is simple in form, effective in operation, and which may be provided at a comparatively low cost. As illustrated, a pulley 52 provided with eccentrically mounted weights 53 is rotatably mounted upon a shaft 54 and prevented from endwise movement by collars 54a. The opposite ends of shaft 54 fit in recesses in beams 12 and 13 and are secured thereto by means of U-bolts 55 and 56 as shown more particularly in Figs. 1 and 8.

Pulley 52 may be of any desired form and the weights may be applied thereto in any desired manner. For instance, the pulley may be provided with pockets in which weights formed of a suitable metal may be cast or in which the weights may be inserted and retained by suitable covers. As illustrated, weights 53 are bolted to the web of the pulley as indicated at 57 and during the rotation of the pulley which may be effected by any desirable means, such as by a motor

58 connected to the pulley by suitable means, such as a belt, the table is vibrated in opposite directions against the action of compressed springs 43 and 51.

5 Means are also provided to vary the transverse inclination of the deck to compensate for variation in feed so that the line of separation of the concentrate can be held coincident with the tip ends of the riffles and for this purpose an angle iron 58a is secured to beam 13 and is provided with an apertured lug 59 to receive a screw 59a provided with a crank 59b. Screw 59a also extends through a threaded collar 59c secured to a strip 59d which in turn is secured to slide 24, and thus when crank 59a is turned in one direction, the slide is moved rearwardly to raise cross pieces 19 to 22, thereby increasing the inclination of the deck and when the crank is operated in the opposite direction slide 24 is moved forwardly, permitting the cross pieces 19 to 22 to slide into the lower portion of the depressions or notches, thereby decreasing the inclination of the deck.

As the mineral constituents of the ore are moved along and beyond the riffles, improved means are provided to regulate the amount of dressing water supplied to the deck. For this purpose, a plurality of juxtaposed adjustable gates 60 having recesses 61 at their upper ends are provided at that side of a water dressing trough 62 which is in nearest proximity to head board 33, the gates being yieldingly held to the bottom of the trough by rods having a head 64 extending above the bottom of the recess and a spring 65 compressed between the bottom of the recess and the head. Any one or more of these gates may thus be opened to any desired extent to provide the requisite quantity of dressing water.

The operation of my improved table will now be apparent. The deck of the table is first adjusted to provide the proper inclination and ore pulp is fed to the trough 3, a portion of which passes through openings 30a into trough 3a and is fed from both troughs through openings 32 on to the deck of the table. As the pulp passes over the riffles, the mineral constituent and a portion of the gangue settle in the grooves between the riffles and the remainder of the gangue is carried over the riffles and is discharged along the tailings side as indicated by the numeral 66. The mineral constituent of the ore is moved longitudinally of the deck by the vibrating movement of the deck and as it passes forwardly, water which is supplied to trough 67 passes through an opening 68 in a partition 69 into trough 62 and is fed to the deck through adjustable gates 60, washing the gangue from the ore as it passes between and beyond the riffles, the water and gangue being discharged at the tailings side of the table and the mineral constituents being finally discharged at the concentrate end into a suitable trough 70.

The action of the weights in causing vibration of the table is clearly indicated in Figs. 2 and 4. Assuming that the parts are in the position indicated in Fig. 2 with slats 35 in vertical position, cross pieces 15 and 17 spaced from recesses 45 and 44 in standards 38 and 39, respectively, springs 48 and 51 compressed and weights 53 in a neutral position, when pulley 52 is rotated in a clockwise direction as indicated by the arrow, slats 35 will be flexed from their vertical dotted line position as shown in Fig. 4 to the full line position and cross pieces 15 and 17 will be moved to the left until cross piece 17 enters recess 44 and engages standard 39. During this movement

spring 51 is further compressed and the compression upon spring 48 is partially released. As pulley 52 is rotated further in the direction of the arrow, the effect of weights 53 gradually decrease and compressed spring 51 now being stronger than spring 43 gradually returns the parts to their original position as the weights approach and finally reach a position opposite to that shown in Fig. 2. Upon further movement of the pulley in the same direction, the weights will approach and finally reach a position opposite to that shown in Fig. 4 at which time the slats in turn will be flexed in a direction opposite to that shown in Fig. 4, cross piece 15 will enter recess 45 and engage standard 38, the compression upon spring 48 will be increased and the compression upon spring 51 will be partially released, the parts assuming the position shown in Fig. 2 when the pulley is finally returned to its original position. While pulley 52 may be operated at any desired speed, it has been found that best results are obtained when it is rotated at a speed of approximately 100 to 200 revolutions per minute with weights varying from 35 to 40 pounds when associated with a frame approximately 11 feet 5 inches long by 2 feet 6 $\frac{3}{4}$ inches wide supported at opposite ends by six 3 inch by $\frac{3}{8}$ inch slats and at the middle by four 3 inch by $\frac{3}{8}$ inch slats.

What I claim is:

1. In an ore concentrator, a longitudinally and transversely inclined table having longitudinally extending riffles on its upper surface for receiving the mineral constituents of ore pulp, means for passing water over the riffles, means for supporting said table including an upper frame movable in opposite directions from a neutral position and a lower frame, each frame including a pair of longitudinally extending beams and a plurality of spaced cross bars interposed between and secured to the beams for maintaining them in spaced relation, at least some of the cross bars in the upper frame being parallel to some of the cross bars in the lower frame when the upper frame is in neutral position, and flexible slats secured to parallel cross bars in the upper and lower frames at a plurality of points along said frames for yieldingly supporting the upper frame, said slats being vertically disposed when the upper frame is in neutral position, a pair of spaced standards, each of which is secured at its lower end to one of the cross bars in the lower frame and has an upper end adjacent to but spaced from an associated parallel cross bar in the upper frame when the upper frame is in a neutral position, resilient means for normally maintaining each associated upper cross bar in spaced relation to its respective standard when the upper frame is in neutral position, and movable means associated with the upper frame for alternately forcing the cross bar adjacent each standard into engagement with its respective standard against the force of said resilient means.

2. In an ore concentrator, a longitudinally and transversely inclined table having longitudinally extending riffles on its upper surface for receiving the mineral constituents of ore pulp, means for passing water over the riffles, means for supporting said table including an upper frame movable in opposite directions from a neutral position and a lower frame, each frame including a pair of longitudinally extending beams and a plurality of spaced cross bars for maintaining the beams in spaced relation, at least some of the cross bars in the upper frame being parallel to corresponding cross bars in the lower frame when

the upper frame is in neutral position, and flexible slats secured to upper and lower parallel cross bars at a plurality of points along said frame which are vertically disposed when the upper frame is in neutral position, a pair of spaced standards, one of which has its lower end secured to one of said lower cross bars and a recessed upper end with its recess spaced from but arranged adjacent to and facing a parallel upper cross bar and the other having its lower end secured to the opposite side of a second lower cross bar and a recessed upper end with its recess facing the recess in the other standard and being arranged adjacent to and facing but spaced from an upper cross bar parallel to the second lower cross bar when the upper frame is in a neutral position, resilient means associated with each standard which has the tendency to force the cross bar into the recess of its associated standard against the opposing force of the other resilient means, and movable means associated with the upper frame for alternately forcing the cross bar adjacent each standard into the recess of its associated standard against the force of the resilient means associated with the other standard and its associated cross bar.

3. In an ore concentrator, a longitudinally and transversely inclined table having longitudinally extending riffles on its upper surface for receiving the mineral constituent of ore pulp, means for passing water over the riffles, means for supporting said table including an upper frame movable in opposite directions from a neutral position and a lower frame, each frame including a pair of longitudinally extending beams and a plurality of spaced cross bars interposed between and secured to the beams for maintaining them in spaced relation, the cross bars in the upper frame being parallel to the cross bars in the lower frame when the upper frame is in neutral position, a plurality of flexible slats affixed to upper and lower parallel cross bars at opposite ends and centrally thereof, the flexible slats at one end of said frame being affixed to the parallel upper and lower cross bars at a side opposite to that at which the flexible slats are affixed to the corresponding upper and lower parallel cross bars at the opposite end of said frame, a pair of spaced standards, one of which has its lower end secured to one of said lower cross bars and a recessed upper end with its recess spaced from but arranged adjacent to and facing an associated parallel upper cross bar and the other having its lower end secured to the opposite side of a second lower cross bar and a recessed upper end with its recess facing the recess in the other standard and being arranged adjacent to and facing but spaced from an upper associated cross bar parallel to the second lower cross bar when the upper frame is in a neutral position, resilient means associated with each standard and the cross bar adjacent thereto for normally maintaining each associated cross bar in spaced relation to the recess in its associated standard when the slats are in a vertically disposed position, and movable means associated with the upper frame for flexing said slats in opposite directions from their vertical position and alternately forcing the cross bars adjacent each standard into the recess of its associated standard against the force of the resilient means associated with the other cross bar.

4. In an ore concentrator, a longitudinally and transversely inclined table having longitudinally extending riffles on its upper surface for receiving the mineral constituents of ore pulp, means for

passing water over the riffles, means for supporting said table including an upper frame movable in opposite directions from a neutral position and a lower frame, each frame including a pair of longitudinally extending beams and a plurality of spaced cross bars interposed between and secured thereto for maintaining the beams in spaced relation, the cross bars in the upper frame being parallel to the cross bars in the lower frame when the upper frame is in a neutral position, a plurality of flexible slats affixed to upper and lower parallel cross bars at a plurality of points along said frame which slats are vertically disposed when the upper frame is in neutral position, a pair of spaced standards, each of which is positioned substantially the same distance from the opposite ends of the beams and each of which has a lower portion secured to a lower cross bar and an upper recessed end which is adjacent to and facing but

spaced from an upper parallel cross bar when the upper frame is in neutral position, means for bracing said standards to each other and to the lower frame, said standards being secured to the opposite sides of the respective lower bars and the recesses in the upper ends being faced toward each other, resilient means associated with each standard and its adjacent upper cross bar for maintaining each of the upper cross bars in spaced relation to the recess in its associated standard when the upper frame is in neutral position, and movable means associated with the upper frame for flexing said slats in opposite directions from their vertical position to alternately force the upper cross bar adjacent each standard into the recess of its associated standard against the force of the resilient means associated with the other standard.

ERVIN O. OBERDICK.
